UNITED STATES PATENT OFFICE

173,045

BORESCOPE

Snow W. Smart, Chicago, Ill.

Application June 11, 1952, Serial No. 20,118

Term of patent 14 years

(Cl. D57—7)

To all whom it may concern:

Be it known that I, Snow W. Smart, a citizen of the United States, residing at Chicago, in the county of Cook and State of Illinois, have invented a new, original, and ornamental Design for a Borescope, of which the following is a specification, reference being had to the accompanying drawing, forming a part thereof.

Fig. 1 is a side elevational view of a borescope embodying my new design;

Fig. 2 is a bottom plan view thereof;

Fig. 3 is a top plan view thereof; and

Fig. 4 is a vertical cross-sectional view thereof taken along the line 4—4 of Fig. 3.

I claim:

The ornamental design for a borescope, substantially as shown.
